UNITED STATES PATENT OFFICE.

WILLIAM D. KELLY, OF CHICAGO, ILLINOIS, ASSIGNOR TO BURKEL MANUFACTURING COMPANY, OF CHICAGO, ILLINOIS, A CORPORATION OF ILLINOIS.

GLUING-MACHINE.

1,165,416.

Specification of Letters Patent. Patented Dec. 28, 1915.

Application filed March 24, 1913. Serial No. 756,351.

To all whom it may concern:

Be it known that I, WILLIAM D. KELLY, a citizen of the United States, residing at Chicago, in the county of Cook and State of Illinois, have invented certain new and useful Improvements in Gluing-Machines, of which the following is a specification.

This invention relates to gluing machines such as are generally employed in wood-working shops to facilitate the application of glue to the surfaces or edges of articles to be joined and has more particular reference to that part of the machine customarily known as the glue plate and designed to apply the glue to the surface to be joined.

Glue plates of various types have been employed prior to my present invention and, while they are capable of applying glue to a smooth surface in a very satisfactory manner, they are not suitable for applying glue to tongues and grooves, mortises and tenons, or articles having rough and irregular surfaces which it is often desirable in the wood-working art to join together.

My present invention has for one of its primary objects the provision of a glue plate which will be adapted to apply glue in a satisfactory manner to either flat or rough and irregular surfaces.

Another object of the invention is to provide a glue plate which will normally present a flat glue-carrying surface, which surface, however, shall be so constructed that its various component parts will be adapted to yield under pressure of the article to be glued, so that the surface will conform to and substantially assume the general shape of the surface presented to it for the reception of the glue.

A further object is to provide a machine with a work support adapted to hold the work or articles to be glued in position above the glue plate and in the path of the travel thereof to receive a supply of glue when the plate is elevated into contact therewith.

For the purpose of facilitating the explanation of my invention, I have shown on the accompanying drawings a gluing machine of conventional form equipped with a preferred and practical embodiment of my invention from which, when considered in conjunction with the following description, the principle of my invention will be readily understood.

Referring to the drawings—Figure 1 is a side elevation partially in section of a machine embodying my invention; Fig. 2 is an enlarged elevation of my improved glue plate; Fig. 3 is a fragmentary plan view thereof; Fig. 4 is a fragmentary end elevation looking toward the left in Fig. 2; Fig. 5 is a fragmentary sectional view taken substantially on the line 5—5 of Fig. 1; Fig. 6 is a fragmentary sectional view similar to Fig. 1, showing another form of glue plate; Fig. 7 is a plan view of the plate shown in Fig. 6; Fig. 8 is a perspective view of one of the elements of the plate shown in Figs. 6 and 7; Fig. 9 is a plan view of another form of glue plate; Fig. 10 is a perspective view of one of the elements of the glue plate shown in Fig. 9; and Fig. 11 is a fragmentary sectional view similar to Fig. 6 showing another manner of mounting the glue-carrying elements.

On the drawings reference character 6 indicates a standard or table supporting a water tank 7 which may be heated in any suitable manner, a steam coil 8 being shown in the present instance as illustrative of one mode of heating the same. The water tank carries two or more upwardly extending studs or pins 9 which serve as guides for a frame or rack 11 upon which the glue plate is mounted. The glue pot 12 is arranged within the water tank so that the rack or frame 11 with the glue pot thereon may be immersed in the hot glue in the glue pot. A rock-shaft 10 is mounted in the frame 6 and provided at its ends with arms 13 which, in turn, are connected to the ends of the rack 11 by links 14, whereby upon oscillation of the shaft 10 the rack and glue plate are submerged in the hot glue and lifted out into the position shown in Fig. 1, so that the glue carried by the plate may be applied to the article to be glued. A pedal 15 is pivotally mounted, preferably on a cross-shaft 16, near the floor, in position to be operated by the foot and is connected by a link 17 with an arm 18 fixed on the rock-shaft 10. A spring 19 and suitable counter-weights 21 may be employed, if desired, to facilitate the raising and lowering of the glue plate. The mechanism thus far described may be of any well known or preferred construction, but preferably designed so that the rack 11 with the glue plate thereon will be normally submerged in the hot glue.

My novel glue plate, designated generally by reference character 22, is adapted to rest upon and be carried by the rack 11. Since it is often desirable to apply glue to the edges of stock or to tongues or grooves, I have so designed and constructed my glue plate that it is capable of conforming in a general way to the shape of the article against which it is pressed, thereby carrying the glue into the depressions or grooves of the article with the result that a uniform layer of glue is applied to the entire surface engaged by the glue plate.

By reference to Fig. 2 it will be observed that one form of my new plate comprises a base 23, adapted to rest upon the rack 11, and a plurality of glue-carrying elements 24, each preferably having one end seated in or suitably connected to the base 23. The individual glue-carrying elements forming the glue-carrying surface may be of any suitable construction, but I have found that a very practical and efficient structure may be formed by making the individual elements 25 out of resilient wire of any preferred cross-sectional shape, each being bent to provide a shank 25 extending at an angle from the base 23, a top portion 26 disposed in a substantially horizontal plane, and a depending end 27, all as shown in Fig. 2. The glue-carrying elements are preferably mounted on the base 23 so that their tops or glue-carrying portions 26 are arranged in staggered relation and all lie in a common 30 and substantially horizontal plane when the plate is mounted on the supporting rack 11. The ends 27 are turned downwardly, as shown, to maintain the relative positions of the elements and prevent them from lapsing over each other, particularly when 35 one or more of them is depressed relatively to the other. Since the material from which the glue-carrying elements are formed is resilient in character, it will be obvious that 40 the shank will yield sufficiently to permit the depression of one or more of the elements relatively to the others when pressure is applied to its upper surface or glue-carrying portion 26. This construction, therefore, affords a yielding surface which is adapted 45 to conform automatically to any irregularities in the surface of the article to be glued. I have shown, for instance, in Figs. 1 and 5, a piece of stock 28 as disposed upon 50 the upper surface of the glue plate, this stock being shown as provided on its lower face with tongues 29 and grooves 31. From Fig. 5 it will be observed that when the plate is pressed against this piece of stock 55 the glue-carrying elements beneath the tongues will be depressed while the intermediate elements will enter the grooves 31, thereby applying glue to the bottoms of the grooves as well as to the outer faces and sides 60 of the tongues. It will be understood, of

course, that the tongue and groove formation is shown merely for purposes of illustration and that the surface of the plate is capable of conforming to any irregularities in the surface of the article or stock to be glued.

For the purpose of supporting the work in position to receive the glue from the plate as the plate is moved into operative relation therewith, I have provided a plurality of supports which are shown as carried 70 by the glue pot 12 at the ends of the plate. The stock is laid upon these supports and then by means of the treadle and operating mechanism actuated thereby the plate is elevated into engagement with the stock to 75 deposit a quantity of glue upon the lower face of the stock.

The plate which I have illustrated in Fig. 1 is made up of two sections, but, it will be obvious, that the plate might be made in 80 any desired number of sections and the work support likewise might be of any other preferred construction. It will be understood, of course, that the rack 11 is merely 85 a frame for supporting the glue plate which 90 permits the glue to drain back into the glue pot when the frame and plate are raised. Normally, the plate is immersed in the hot glue but, when it is desired to apply glue 95 to an article, the plate is elevated into the 100 position shown in Fig. 1 by the mechanism previously described, whereupon the surface 105 of the stock engaged thereby receives a supply of the glue. The surplus glue runs back into the glue pot as the plate is raised. 110 If a smooth or flat piece of stock is to be glued the glue-carrying elements will be depressed but slightly and all an equal amount, but, if the stock is of tongue and groove formation, or has any irregular surface, the 115 glue-carrying elements will be depressed individually proportionately to the pressure 120 exerted upon them.

In the form of my invention illustrated in Figs. 6, 7 and 8 the glue plate designated 115 generally by reference character 32 comprises a series of glue-carrying elements 33 in the form of narrow bars or plates arranged in parallel relation upon the rack 11. These bars or plates may be of any preferred width and are preferably provided with apertures 34 through which the glue 120 may drain back into the glue pot when the plate is raised. Each element is designed to yield independently of the others under the 125 influence of pressure exerted upon its upper face and, for the purpose of yieldingly supporting the elements with their upper faces normally in a substantially horizontal plane, I have provided coiled expansion springs 130 128 disposed beneath and preferably adjacent the ends of each element, whereby the elements are yieldingly supported upon the rack 11. For the purpose of preventing displacement of the elements and of guiding 135

them in their upward and downward movements I have provided for each element a pair of links 36 pivotally connected at one end to the rack 11 by socket and pin connections 37, the other ends of the links being slidably and pivotally connected to an element 33 by slot and pin connections 38. Since the links 36 of each pair are oppositely disposed, it will be manifest that the glue-carrying elements will be restrained by the links to a substantially right line up and down movement. The elements, therefore, are each yieldingly and independently supported and guided so that each of them may yield independently of the others when pressure is applied to its upper surface. In practice the width of the individual elements will usually be determined by the character and shape of the work to be glued by the machine.

In Figs. 9, 10 and 11 I have illustrated another form of glue plate designated generally by reference character 39, this plate being also made up of a series of individual glue-carrying elements, one of which is shown in perspective in Fig. 10. These elements, as will be obvious from this figure, comprise a bar or plate 41 provided with a series of elevations or glue-carrying projections 42, the bars between the individual projections being preferably provided with perforations 43 through which the glue may drain back into the glue pot as the plate is raised. For some kinds of work this form of plate is preferable to that shown in Figs. 1 to 5, or that shown in Figs. 6 to 8, but, it will be understood that my invention does not reside in the specific construction of the glue-carrying elements, since the structure 40 of these elements may be varied to suit the requirements of the work to be glued.

While the elements 41 of the plate 39 may, if desired, be mounted in the manner shown in Fig. 6, I have shown in Fig. 11 another manner of mounting the elements which, in some instances, may be preferable. The glue-carrying elements 41 as shown in this figure are connected to the rack 11 by means of links 44 pivotally connected at 45 to the rack and at 46 to an element 41. The links in this instance are both disposed in the same direction so that a reciprocatory movement is imparted to the glue-carrying element when pressure is exerted upon its upper surface. The elements are each normally retained substantially in the position shown by means of contraction springs 47 attached at one end to an end of the rack 11 and at the other end to an element 41. The elements are, therefore, yieldingly supported

to normally present a substantially flat glue presenting surface, but, each of the elements is adapted to yield independently of the others, upon application of pressure to its upper face. While the glue-carrying plates 65 32 and 39, illustrated in Figs. 6 to 11, inclusive, are shown as consisting of glue-carrying elements, the lengths of which are substantially equal to the length of the plate, it will be manifest that the elements may be 70 of any desired length, a number of them being disposed in longitudinal alinement to make up a plate of the requisite length, each element, of course, being independently mounted to yield independently of the others.

It is believed that my invention will be fully understood from the foregoing and, since many modifications in the details of construction shown and described will suggest themselves to those skilled in the art, it will be obvious that the invention is not restricted to the structural details disclosed but is capable of variations within considerable limits without exceeding the scope of 85 the following claims:

I claim:

1. A glue plate for a gluing machine, comprising a plurality of glue-carrying elements, each having an inclined shank, a substantially horizontal top and a downturned end, said elements being arranged in staggered relation.

2. In a gluing machine, the combination of a glue pot, a vertically reciprocable frame, and a glue plate carried by said frame comprising a plurality of glue-carrying elements, each having an inclined shank, a substantially horizontal top, and a down-turned end.

3. In a gluing machine, the combination of a glue pot, a vertically reciprocable frame, a glue plate carried by said frame comprising a plurality of glue-carrying elements, each having an inclined shank, a substantially horizontal top, and a down-turned end, and means for reciprocating said frame to move it into and out of said glue pot.

4. A glue plate for a gluing machine comprising a vertically reciprocable frame, a plurality of glue-carrying elements mounted thereon and arranged in parallel relation, each of said elements having an inclined shank secured to said frame, a substantially horizontal top, and a down-turned end.

WILLIAM D. KELLY.
